HOT BEVERAGE MERCHANDISER

Walter E. Moore, Bel-Nor, Mo., assignor to UMC
Industries, Inc., St. Louis, Mo., a corporation of Delaware

Filed Dec. 22, 1966, Ser. No. 5,147

Term of patent 14 years

(Cl. D52—3)

Fig. 1

Fig. 3

Fig. 2

Fig. 4

FIG. 1 is a top plan view of a hot beverage merchandiser, showing my new design;

FIG. 2 is a front elevation;

FIG. 3 is a side elevation; and

FIG. 4 is a perspective view of the merchandiser.

The rear of the hot beverage merchandiser is substantially flat and plain in appearance, and the undisclosed side is substantially the same in appearance as the side shown.

I claim:

The ornamental design for a hot beverage merchandiser, substantially as shown and described.
